CLAIM

The ornamental design for a hangboard, as shown and described.

DESCRIPTION

FIG. 1 is a top perspective view of a hangboard in accordance with the present invention.

FIG. 2 is a bottom perspective view thereof.

FIG. 3 is a top plan view thereof.

FIG. 4 is a bottom plan view thereof.

FIG. 5 is a left side view thereof.

FIG. 6 is a right side view thereof.

FIG. 7 is a front view thereof; and,

FIG. 8 is a rear view thereof.

The broken lines in the drawings depict portions of the hangboard that form no part of the claimed design.
